UNITED STATES PATENT OFFICE.

WORTH R. BARRINGER, OF GRAND JUNCTION, COLORADO.

EVAPORATION-REFRIGERATOR.

1,239,250.

Specification of Letters Patent.

Patented Sept. 4, 1917.

Application filed August 19, 1916. Serial No. 115,857.

To all whom it may concern:

Be it known that I, WORTH R. BARRINGER, a citizen of the United States, residing at Grand Junction, in the county of Mesa and State of Colorado, have invented certain new and useful Improvements in Evaporation-Refrigerators, of which the following is a specification, reference being had to the accompanying drawings.

- 10 This invention relates to the art of refrigeration and particularly to refrigerating appliances based upon the principle of evaporating water from the surface of a water absorbent container.
- 15 The general object of my invention is the provision of a refrigerating device which comprises an outer water container formed of such material that the water may evaporate from the exterior surface thereof and 20 an inner food receptacle inclosed within the container, the evaporation of the water from the container acting to cool the water within the container and thus relatively low temperature being communicated to the food.
- 25 A further object of this invention is the provision of a refrigerating device comprising a food receptacle and an outer double walled bag adapted to hold water and permit the evaporation of the water from the 30 outer surface thereof, there being means provided whereby access may be had to the interior of the receptacle.

Other objects have to do with the detailed construction of the receptacle and the water bag.

My invention is illustrated in the accompanying drawings, wherein:

Figure 1 is a vertical sectional view through a refrigerating device constructed 40 in accordance with my invention;

Fig. 2 is a front elevation of the device with the walls thereof broken away to show the interior of the construction; and

Fig. 3 is a perspective view of the water bag.

Fig. 4 is a vertical sectional view of a modified form of refrigerating receptacle.

Referring to these figures, it will be seen that my invention comprises an outer container or bag, as it may be termed, designated generally 10, which may be of any suitable form, but is illustrated as approximately quadrangular and which is formed of canvas or like material which will permit

55 a slight amount of water to pass through the meshes of the canvas and be evaporated

from the surface thereof. The outer container is formed of a plurality of pieces of material stitched to each other in the ordinary fashion. Disposed within the outer container and in spaced relation thereto, there is an inner wall or container 11, also made of canvas, and also quadrangular in form, the front wall of this inner container being stitched to the front wall of the outer container as at 12. It will be seen that a water space 13 is formed between the outer and inner walls. The front of the outer container and the corresponding side of the inner container are formed to provide an opening 14 whereby access may be had to the interior of the inner container, this opening being normally closed by a flap 15 of canvas or like material which is stitched to said front wall and hangs below the opening 14.

Disposed within the inner container 11 is a receptacle 16 illustrated as quadrangular in form, and illustrated as formed of perforated sheet metal, though it may be 50 made of wire gauze or any other suitable stiff material which will hold the inner container expanded and permit the placing of food within the inner container. The top 17 of the receptacle is not perforated.

For the purpose of sustaining the inner end of the inner container 11 and of the receptacle 16, I provide the straps or bands 18 which extend downward from the upper rear corners of the outer container and are 60 connected to the upper rear corners of the inner container, these bands being made of canvas, leather, or other flexible material.

Eyes 19 are attached to the rear wall of the outer container at the upper end thereof, as 65 shown clearly in Fig. 3 and it will be seen that the weight of the food receptacle and its contents will be carried by the bands 18 directly to these corners of the outer container which are provided with the eyes 19. 100 These eyes 19 are for the purpose of suspending the container. The upper wall of the outer container is formed with a water inlet nipple 20 closed by a cap 21, and the side wall of the container 10 at its lower 105 end is formed with an outlet nipple 22 closed by a cap 23. The flap 15 or door may be held closed by any suitable catch and I have shown for this purpose a socket 24 and a stud 25 engageable therewith.

In Fig. 4 I show a vertical sectional view through a modified form of container which

is particularly adapted to be carried by travelers or soldiers. In this device there is an outer bag or container 26 also of canvas or like material, the bag being simply formed of a front and back piece stitched together at the edges or otherwise formed so that it will contain water and provided with a nipple 27 at its upper end and eyes 28, whereby it may be supported. The front wall of the bag is cut away as at 29 and disposed within the bag is a receptacle 30 of sheet metal, this receptacle being solid and having an opening 31, the sheet metal surrounding the opening being overturned upon the canvas at the margin of the opening 29 so as to form a water-tight joint. A flap 32 is stitched to the front wall above the opening 29, and at its lower end this flap is provided with a button or other suitable means for holding it closed. The upper end of the bag 26 is reinforced by a transverse bar 33 to which the rings or eyes 28 are operatively connected.

A strap, band or cord 34 is operatively connected to the rear end of the receptacle 30 and extends upward to the top of the outer receptacle 26 and is attached to said outer receptacle at the point of attachment of the outer receptacle to the transverse bar 33, so that the pull or strain on the flexible connection 34 will not deflect or deform the bag 26 but will come directly upon the cross bar 33 and thus upon the straps supporting the receptacle from the shoulder. It will be seen that in Figs. 1 and 2, the bands 18 extend upward to the upper rear corners of the receptacle and transmit the strain due to the weight of food within the receptacle 11, directly to the eyes 19 to which the supporting straps are connected. Thus the weight of the food within the receptacle 11 does not place any strain upon the bag itself, and does not deform the bag. It is, of course, obvious that without these straps 18 or the flexible connection 34, the inner end of the food receptacle would sag, even though the latter were made of stiff sheet metal and this is particularly true of the construction shown in Figs. 1 and 2 where the receptacle 11 is formed of canvas.

The lower end of the water receptacle 26, in Fig. 4 is provided with an outlet or discharge opening closed by a cap 35.

In use, the water space is filled with water and the device suspended in a draft. The water will ooze through the outer container and be evaporated from the surface thereof, thus cooling the water in the water space and also cooling the contents of the receptacle 16 or 30. It will be seen that I have provided a combination water cooler and container and refrigerator for articles of food and that the device is adapted to be used either in the home or out of doors by farmers, ranchers, soldiers, travelers and the

like who cannot easily obtain ice. The device is very simple and cheap, is thoroughly effective in use and may be made so that it will occupy but a small space. I do not wish to be limited to the form of the device as illustrated as it is obvious that other forms may be used. The device may be made either on a relatively large size or nearly as small as the ordinary canteen used by soldiers. Food may thus be carried as well as water and the constant evaporation of the water will keep the water cool and sweet and also keep cool the contents of the refrigerating compartment.

Having described my invention, what I so claim is:

1. A refrigerating device of the character described comprising an outer casing or container of flexible absorbent material having a normally closed opening at one end, a food receptacle disposed within said container and spaced therefrom on all sides but one, this one side of the receptacle and the container having water-tight engagement with each other and being formed to provide an opening whereby access may be had to the receptacle, a cover for said opening, and flexible supporting members operatively engaging the upper end of the outer container and the upper inner end of the receptacle.

2. A refrigerating device of the character described comprising an outer bag-like container of flexible absorbent material, a food receptacle disposed within the container, one wall of the food receptacle being abutted against and having water-tight engagement with one side wall of the container, the last named container and receptacle walls being formed to provide an opening into the receptacle, a cover for said opening, flexible means for supporting the inner end of the receptacle from the upper end of the container and means disposed at the outer end of said container whereby the container may be supported, said flexible supporting means being engaged with the upper end of the container immediately adjacent to the point of attachment of the container supporting means.

3. A refrigerating device of the character described including an outer bag-like container of flexible absorbent material, a receptacle disposed within said container and designed to receive food, one wall of the receptacle being abutted against one wall of the container, said walls being formed with an opening whereby access may be had to the receptacle, a wall of flexible absorbent material surrounding the receptacle, there being a water space between the outer container and said inner wall and receptacle, flexible means for supporting the inner end of the receptacle and wall from the upper end of the container, and means whereby water may be filled into or discharged from the

the container, the walls of the receptacle being formed of foraminous relatively stiff material.

4. A refrigerating device of the character described comprising an outer container of canvas having an opening in one wall, a receptacle disposed within the container and having an opening in one wall, the open wall of the receptacle having water-tight engagement with the open wall of the container, means for supporting the inner end of the receptacle from the upper end of the container and including flexible elements extending upward from the inner end of said receptacle to the upper end of the container

and attached to said upper end, a flexible flap normally closing the opening in the container, means whereby water may be filled into or discharged from the container, and means for supporting the container, said supporting means being attached to the container at points adjacent the point of attachment of said flexible elements.

In testimony whereof I hereunto affix my signature in the presence of two witnesses.

WORTH R. BARRINGER.
